UNITED STATES PATENT OFFICE

EDWIN STAUTER AND LEWIS N. KIMERER, OF PARIS, TEXAS, ASSIGNEES TO AMES SHOVEL & TOOL COMPANY, OF BOSTON, MASSACHUSETTS, A CORPORATION OF NEW JERSEY

MAKING SHOVEL HANDLES

Application filed December 27, 1927. Serial No. 242,903.

This invention pertains to tool handles and relates more particularly to an apparatus for making wooden shovel handles of the split-D type.

5 Handles for shovels, spades and similar tools usually comprise a wooden haft which is split at its upper end to provide a fork or yoke whose side arms are spread apart and held in diverging relation by means of a grip bar inserted between their ends and secured by means of a rod or bolt extending axially through the grip bar. To form the forked end of the wooden haft, the haft is commonly saw cut longitudinally along its axis; the divided end is treated with steam or other softening agent to render it more pliable; and the arms of the fork are then spread to the desired shape by a molding apparatus which fixes the configuration of the fork and holds 10 the haft until the wood is dried. The present invention has mainly to do with means for spreading and shaping the forked end of the haft.

The practice heretofore followed in shaping 25 the fork generally has consisted in forcing the divided end of the wooden haft endwise into a metal mold having a bifurcated channel defined by diverging outer walls and a V-shaped inner wall, said walls being integral 30 with the base of the mold and consequently fixed in position with respect to each other. The apex of the V-shaped portion of the mold enters the saw cut in the haft as the haft is driven into the mold, and spreads the tines 35 of the fork into the bifurcated channel within which the fork is retained until the wood has dried and the shape of the fork has become set. The forked haft is then pried upwardly from the mold, and is ready for the 40 attachment of the grip bar.

The use of this prevailing method frequently results in splintering or breaking the arms of the fork, particularly if the grain of the wood is not true, and often produces lop-sided handles, especially if the saw cut is not exactly medial; and the waste of material owing to these causes is considerable. Such objectionable results are believed to be due to the rigidity of the walls of the mold 45 and to the fact that the necessary width of the

channels prevents the spaced walls from properly supporting both sides of the forked arms. The method is furthermore expensive, for molds of this type are costly; a complete mold is necessary for shaping each handle; and although the molds may be used for successive spreading operations, a considerable number must be tied up during the drying period.

It is the purpose of this invention to overcome these objections by the provision of improved means for so spreading and shaping the divided end of the wooden haft that the possibility of splitting or breaking the wood is largely obviated and the production of lop-sided handles is practically eliminated. To this end, the improved apparatus comprises a mold which in exterior conformation is similar to the prior molds but in which the interior, fixed V-shaped portion is omitted; and a shoe slideable within the mold and having a pointed end and diverging sides adapted to spread the divided end of a haft resting in the mold and to press the arms of the fork against the outer wall of the mold, when the shoe is forced into proper position. A further object of the invention is to provide a retaining member adapted to be removably carried by the shoe and to hold the arms of the fork in proper position within the mold, so that the shoe may be removed from the mold and immediately used in another operation. Further objects reside in the improved construction hereinafter described and pointed out in the appended claims, which permit the immediate utilization of the whole or a portion of the mold in a successive operation as soon as one spreading operation is completed.

Preferred embodiments of the improved apparatus are illustrated in the accompanying drawings, in which:

Fig. 1 is a plan view of the mold with the divided haft in position for the spreading operation;

Fig. 2 is a similar view showing the position of the shoe during an intermediate stage of the spreading operation;

Fig. 3 shows the position of the parts at the completion of the spreading operation and prior to the removal of the shoe;

Fig. 4 illustrates the position of the retaining member after removal of the shoe, and also shows a modified construction of the mold;

5 Fig. 5 is a transverse section on the line 5—5 of Fig. 3;

Fig. 6 is a plan view of the shoe with the upper portion thereof removed to show the normal position of retaining member;

10 Fig. 7 illustrates an optional form of retaining member as applied to the forked arms; and

Fig. 8 is an end view of the mold and shoe equipped with the retaining member of Fig. 7.

The mold is preferably cast of malleable iron or other suitable metal and may be formed with a base 9 and integral side walls 10 which diverge toward the outer end of the mold from a constricted throat 11 and which define the external shape of the finished handle. The outer end of the wooden haft 12 having the longitudinal saw cut 13 is placed in the mold substantially as shown in Fig. 1, with the saw cut terminating at the throat of the mold. The inner end of the mold and the haft are then suitably braced to prevent axial movement of the parts during the spreading operation which, it will be understood, may be performed by appropriate machinery.

The slidable shoe 14 may be formed of a solid block of metal or of flat sections, as hereinafter described, and is substantially V-shaped in plan, as illustrated in Figs. 2 and 3, so that its apex will enter the saw cut in the haft and spread the arms 15 of the fork against the side walls 10 of the mold, when the shoe is forced toward the throat of the mold.

40 As the shoe is slidable transversely as well as longitudinally upon the base of the mold, it is apparent that the arms 15 will be forced into close contact with the side walls 10 even though the saw cut is not exactly medial of the haft. When the shoe is forced home (Fig. 3) it accordingly exerts uniform contacting pressure upon the inner sides of the arms 15, and the walls 10 afford resisting support to the outer sides of the arms throughout their length; thus obviating to a large degree the danger of splitting the wood during the spreading process.

The shoe preferably has an edge recess 16 (Fig. 5) adapted loosely to receive a U-shaped retaining member 17 which may be made of steel or other metal, preferably resilient. The base of the U-shaped piece 17 fits behind the apex of the shoe within the borders thereof and the ends 18 normally spring outwardly of the sides of the shoe (Fig. 6); but when the shoe is forced into the mold the ends 18 are contracted within the recess 16, as indicated in Figs. 3 and 5, by contact with the arms 15. The ends 18 do not, however, bind in the shoe recess, so that the shoe may be removed

from the mold leaving the retaining member to hold the arms 15 against the side walls 10, as shown in Fig. 4, until the wood is dry. The shoe is thus rendered available for use in another spreading operation, with a consequent saving in necessary material and cost of manufacture.

A further saving may be effected by making the whole or a portion of the mold immediately available for a subsequent spreading process. For example, the end portion of the mold may be divided from the throat portion, as at 19, Fig. 4, dowel pins 20 being provided detachably to connect the parts when desired. The outer portion of the mold and the haft with its retaining member may accordingly be removed from the throat portion during the drying period. By providing means which in the drawings is illustrated as hooks 21 at the ends of the retaining member 17, the arms 15 may be held in drying position by said member only, so that the haft may be withdrawn from the mold as soon as the spreading operation is completed (see Figs. 7 and 8). It should be understood that my invention contemplates the use of a retaining member of any suitable shape and having any desired form of means for engaging and holding the arms. In such case, the ends of the walls 10 may be notched or cut away as at 22 to accommodate the hooks 21 or other means when the shoe is forced into the mold.

Although the shoe may, as aforesaid, be formed from a single metal block, it may also be sectional, if desired, to reduce the cost of manufacture when the shoe is to be equipped with the retaining member 17. For example, the shoe may be constructed of flat metal sheets, comprising a base 23, a smaller intermediate spacing piece 24 having a curved end adapted to abut the base of the U-shaped member 17, and a top piece 25 similar in shape to the base 22. These parts may be secured together by bolts 26, or by welding or other suitable means.

Apparatus for making split-D shovel handles, constructed as above described may be prepared at a reasonable cost and may be utilized simply and efficiently to achieve the beneficial results mentioned above. It has been found that the wastage of material caused by splitting the wooden forks and imperfect handle formation when using the former type of mold amounted to approximately sixteen per cent, and that ninety per cent of this wastage is eliminated by utilizing the apparatus herein illustrated. It will be understood, however, that the construction of the elements may be modified to suit particular purposes, without departing from the essence of this invention as defined in the following claims.

We claim:

1. Apparatus for forming tool handles,

comprising a mold having spaced, diverging side walls, a shoe slideable in the mold and adapted to spread the arms of a haft fork against said side walls, and a retaining member removably carried by the shoe and adapted to hold said arms apart, whereby the shoe may be removed from the mold before the formation of the arms has become set.

2. Apparatus for forming tool handles, comprising a mold having spaced diverging side walls, substantially conforming in shape to the exterior contour of the finished handle, a shoe slideable longitudinally and transversely of the mold and adapted to spread the arms of a haft fork against said side walls, said shoe having an edge recess, and a substantially U-shaped retaining member adapted loosely to fit within said edge recess and to engage and hold said arms against said walls, whereby the shoe may be removed from the mold before the formation of the arms has become set.

3. Apparatus for forming tool handles, comprising a mold having a flat base and spaced, diverging side walls substantially conforming in shape to the exterior contour of the finished handle, a shoe freely slideable on said base and adapted to spread the divided arms of a haft fork against said side walls, said shoe having a pointed end and an exterior contour substantially conforming in shape to the inner face of the finished handle and having an edge recess deeper at the pointed end than at the sides of the shoe, and a substantially U-shaped retaining member adapted loosely to fit within said edge recess with the base of the U toward said pointed end, said retaining member serving to lock said arms against said side walls whereby the shoe may be removed from said member and from the mold before the formation of the arms has become set.

4. Apparatus for forming tool handles, comprising a mold having spaced, diverging side walls, a retaining member adapted to hold the arms of a haft fork against said side wall, and means for spreading said arms and forcing said retaining member therebetween, said retaining member having hooked ends adapted to clasp the ends of the respective arms, so that the haft and retaining member may be removed from the mold before the formation of the arms has become set.

5. Apparatus for forming tool handles, comprising a mold having spaced, diverging side walls substantially conforming in shape to the exterior contour of the side arms of a finished handle, and a self-positioning shoe slideable on said base and adapted for both longitudinal and transverse movement relative to the mold, said shoe having an exterior contour substantially conforming in shape to the inner faces of the side arms of a finished handle, whereby, when the shoe is forced into the mold between the arms of a haft, it will

take the proper position and press said arms outwardly against the side walls of the mold and said arms will be tightly clamped between said walls and the said shoe.

6. Apparatus for forming tool handles comprising mold means having spaced, diverging side walls, a wedge-shaped shoe for spreading the arms of a haft outwardly against the side walls of the mold and a retaining member removably carried by the said shoe and having means engageable with the spread arms to hold them in spread position so that the haft may be removed from the mold means after the said shoe has been removed and before the arms become set.

7. Apparatus for forming tool handles, comprising means operable to spread and form one end of a haft to provide diverging side arms and retaining means removably associated with the first mentioned means for engagement with the spread arms of the haft to hold them in position prior of their becoming a set thereby permitting removal from a portion or all of the spreading and forming means.

Signed by us at Paris, Texas, this 20th day of December, 1927.
